UNITED STATES PATENT OFFICE.

JAMES SYLVESTER YOUNG, OF NORTHFIELD, VERMONT.

STONE-SAWING MACHINE.

No. 841,300.

Specification of Letters Patent.

Patented Jan. 15, 1907.

Application filed March 30, 1906. Serial No. 308,986.

To all whom it may concern:

Be it known that I, JAMES SYLVESTER YOUNG, residing at present in Northfield, in the county of Washington and State of Vermont, have invented certain new and useful Improvements in Stone-Sawing Machines, of which the following is a specification.

My invention relates to certain new and useful improvements in stone-sawing machines in which means are provided for mounting the saw-carrying frame so as to be reciprocable in a horizontal plane and so mounted as to eliminate as much friction as possible, and thereby to reduce the power necessary to operate the machine.

My invention also includes a new and useful construction of saw-carrying frame and saw-blades, including means for reënforcing the blade centrally to prevent the same from rising up in the center when the blades are in operation.

With other objects in view than have been heretofore specified the invention comprises certain novel construction, combination, and arrangement of parts, all of which will be first fully described, then specifically pointed out in the appended claims, and illustrated in the accompanying drawings, in which—

Figure 1 is a perspective view of my invention. Fig. 2 is a top plan view thereof. Fig. 3 is a longitudinal section on the line 3 3 of Fig. 2. Fig. 4 is a transverse section on the line 4 4 of Fig. 2. Fig. 5 is a perspective view of the saw-blade-carrying frame detached from the supporting-frame. Fig. 6 is a detail perspective view of one saw-blade. Fig. 7 is a detail sectional view on the line 7 7 of Fig. 6. Fig. 8 is a detail perspective view of the reinforcing bridge member. Fig. 9 is a detail view of one of the blade-clamps coöperating with the bridge member. Fig. 10 is a similar view of a slightly-modified form of blade-clamp. Fig. 11 is a detail view showing a slightly-modified way of connecting the crossed hanger-bars to the saw-beam.

Referring to the accompanying drawings, in which like numerals of reference indicate like parts in all of the figures, 1 designates the main supporting-frame of the machine, which comprises the top rectangular frame 1^a, the bottom rectangular frame 1^b, and corner-posts 1^c, as shown.

2 designates the supplemental posts having a dovetailed groove 2^a, running their entire length, which posts 2 are similarly disposed between the corner-posts 1^c on each

side of the machine. Slidably mounted in the grooves 2^a of the posts 2 are blocks 3, having lugs 3^a upon which walking beams or arms 4 are pivoted. Each block 3 is vertically adjustably held in its respective groove 2^a by screws 5, each of which passes through a threaded aperture 3^b in each block 3, and the screws 5 also serve to adjust a second block 6 in harmony with the block 3, which block 6 is likewise movable in the grooves 2^a and carries guide-rollers 7 for guiding the saw-frame.

An arc-bar 8 is connected with the walking-beam 4, that is pivoted on the lug 3^a of the block 3, the connection being made by crossed arms or haners 10 11.

The arm 10 has an elongated slot to permit passage of the arm 11 for a purpose readily understood.

The side bars 12^a of the saw-carrying frame are pivotally secured to the arc-bars 8, as at 13^a, by hangers 13.

In order to properly adjust all of the blocks 3 and 6 simultaneously, I may provide the screws 5 with pinions 5^a, which mesh with similar pinions 14^a on shafts 14, mounted in bearings on the supporting-frame. These shafts are preferably simultaneously operable through the medium of a cross-shaft 15, having gears 15^b in mesh with gears 14^b on the shafts 14, as clearly shown in Figs. 1 and 2 of the drawings. The shaft 15 may be operated by a crank 15^a or other suitable means.

The saw-carrying frame 12 may be reciprocated in any approved manner, as the means for reciprocating the frame *per se* forms no part of my present invention. By reason of the manner in which the frame 12 is suspended from the supporting-frame, it is capable of reciprocating (within certain limits) in practically a horizontal plane at all times, thus insuring proper operation of the saws without undue friction in the moving parts of the machine.

The saw-carrying frame 12 comprises the side bars 12^a and the end bars 12^b, which bars 12^b are slotted, as at 12^c, to permit passage of the take-up rods 16^a of the saw-holders 16. The holders 16 are secured to the bars 12^b by nuts 16^b, threaded on the rod 16^a, and they are secured to the saw-blades 20 by bolts 17 or otherwise, as might be found convenient.

The saws 20, which also form a part of my present invention, each comprise a skeleton

body formed by the upper and lower bars or strips 20^a 20^b, respectively, joined together by the tie-blade strips 20^c, that are spaced apart at suitable intervals to leave apertures 5 20^d through the body of the blade.

The strips 20^a and 20^b have grooves 20^e to receive the strips 20^c, which where they join the strips 20^a are also cut away, as at 20^f, so that the strips 20^a 20^b have, as it were, a 10 mortise-and-tenon joint with the strips 20^c. The several strips 20^a 20^b 20^c may be secured together by bolts or rivets, as may be found desirable.

The lower bar or strip 20^b between the 15 strips 20^c is provided with dovetailed recesses 20^g in its lower edge to receive the saw-teeth 21 and their locking-wedges 22, which teeth and wedges 21 22, respectively, may be of any approved type, preferably that shown in 20 my Patents No. 816,769, dated April 3, 1906, and No. 816,768, dated April 3, 1906.

Suitable molding-planes 23 may be secured between the teeth 21 by rivets or bolts to the strip or bar 20^b.

25 When the teeth 21 of the type disclosed in my applications hereinbefore referred to are used, as the teeth wear down they can be readily removed and replaced by new teeth or the worn teeth can be cut to a less width 30 with the side groove deepened and be inserted again into the tooth-receiving recesses and held in place by larger wedges 22, and thus made to serve their functions during a longer period until they are too worn to stay 35 in the recesses of the blade.

Several blades spaced at suitable intervals apart are used in my machine, all being laterally adjustably carried by the saw-frame 12, as indicated.

40 25 designates a bridge member, of which one or more may be used, and the bridge member comprises a pair of parallel bars 25^a, spaced apart by one or more blocks 25^b, to which the bars 25^a are secured by bolts 25^c 45 or otherwise, thus forming slots 25^d between the bars 25^a. In the slots 25^d saw-clamps 26 are adjustably held, and each clamp 26 comprises a head 26^a and a shank 26^b, that passes through the slot 25^d and is secured in place 50 by a nut 27, threaded on the shank, as shown in Figs. 1 and 8 of the drawings, or the clamps 26 may be held in place by a wedge 28, passing through an aperture 26^d in the shank 26^b, as indicated in Fig. 10.

55 Each clamp 26 has its head 26^a slotted, as at 26^e, to straddle the upper edge of the saw-blade and hold the blade from movement and reinforce the same.

The bridge 25 is secured to the frame 12 at 60 the desired places by substantially L-shaped irons 29, that are held in place by nuts 30 and 31 on their respective threaded ends 29^a 29^b.

Instead of using a saw-blade formed of sections in a skeleton frame, as indicated herein, 65 in connection with my reciprocating frame

I may use the type of blade disclosed by my copending applications hereinbefore referred to.

From the foregoing description, taken in connection with the accompanying drawings, it is thought the complete construction, operation, and numerous advantages of my invention will be readily understood by those skilled in the art to which it appertains.

What I claim is—

1. In a stone-saw machine, the combination with a main supporting-frame and a saw-carrying frame, of a plurality of means for suspending said saw-carrying frame from said main supporting-frame to be reciprocable in a horizontal plane, said suspending means each comprising a block vertically adjustably held by said main supporting-frame, a walking-beam pivotally secured to said block, a pair of crossed hangers pivotally secured to said walking-beam, an arc-bar pivotally secured to said crossed bars, means connecting said arc-bars with said saw-carrying frame, supplemental blocks carrying friction-rollers for coöperating with the saw-carrying frame and arc-bars, and a plurality of sets of means for adjusting said first-mentioned blocks and said last-mentioned blocks in pairs, substantially as shown and described. 90

2. In a stone-saw machine, the combination with a main supporting-frame and a saw-carrying frame of a plurality of means for suspending said saw-carrying frame, from said main supporting-frame to be reciprocable in a horizontal plane, said suspending means each comprising a block vertically adjustably held by said main supporting-frame, a walking-beam pivotally secured to said block, a pair of crossed hangers pivotally secured to said walking-beam, an arc-bar pivotally secured to said saw-carrying frame, supplemental blocks carrying friction-rollers for coöperating with the saw-carrying frame and arc-bars, and a plurality of sets of means for adjusting said first-mentioned blocks and said last-mentioned blocks in pairs, and means for simultaneously operating all of said adjusting means, substantially as shown and described. 105

3. In a stone-saw, a main supporting-frame, grooved standards forming a part of said frame, pairs of blocks vertically adjustably held in said grooved standards and spaced apart, means coöperatively connecting said blocks together for adjusting the blocks in pairs, a saw-carrying frame, walking-beams pivotally supported on the upper blocks, crossed hangers pivotally secured to each walking-beam, an arc-plate secured to said cross-hangers, and to the saw-frame, friction-rollers on the lower blocks for coöperating with such arc-bars. 110

4. In a stone-saw, a main supporting-frame, grooved standards forming a part of 115

said frame, pairs of blocks vertically adjustably held in said grooved standards and spaced apart, means coöperatively connecting said blocks together for adjusting the 5 blocks in pairs, a saw-carrying frame, walking-beams pivotally supported on the upper blocks, crossed hangers pivotally secured to each walking-beam, an arc-plate secured to said cross-hangers, and to the saw-frame,

friction-rollers on the lower blocks for coöperating with such arc-bars, and means coöperatively connecting each of said block-adjusting means to operate the same in unison substantially as shown and described.

JAMES SYLVESTER YOUNG.
